(57) **CLAIM**

We claim the ornamental design for a X-ray computed tomography scanner, as shown and described.

DESCRIPTION

FIG. 1 is a front, top and right side perspective view of an X-ray computed tomography scanner showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a cross-sectional view taken along the **8-8** Line indicated in the frontal side elevation view with the internal mechanical arrangements omitted thereof.

The portions of the X-ray computed tomography scanner, shown in broken lines form no part of the claimed design.
